ABSTRACT OF THE DISCLOSURE

A hydraulic system effective to remove air from hydraulic fluid at the intake side of a pump and an air-liquid separating structure incorporating an acceleration sleeve, a variable orifice and a disperser sleeve effective to draw said air from said intake side for dispersal within a reservoir.

SUMMARY OF THE INVENTION

A hydraulic system having a pump and return or relief valve discharge conduit and incorporating means for separating air from hydraulic fluid on the suction or intake side of the pump, said means including an acceleration-diffuser sleeve operable in response to the flow of said fluid in the return or relief valve discharge conduit to create a lowered pressure effective to produce such separation. The invention includes a variable orifice in association with the acceleration sleeve and a disperser sleeve formed and adapted to disperse the air and hydraulic fluid downstream of the acceleration sleeve and within a reservoir, a bypass or relief valve structure being associated with the disperser sleeve to protect against back pressure.

This invention relates to hydraulic systems and has particular relation to a system and structure effective to remove air from the hydraulic fluid at the intake side of a pump in the system.

When air, whether dissolved, entrained or otherwise associated with the hydraulic fluid, enters a hydraulic pump, it is compressed and heated, causing sludging, facilitating corrosion, decreasing efficiency and reducing the life of the fluid and the pump. Hence it is one purpose of the invention to provide a hydraulic system and structure effective to substantially eliminate the delivery of air to the intake side of a hydraulic pump.

Another purpose is to facilitate the separation of air from hydraulic fluid at the return or pressure relief valve discharge conduit and thus to increase the density and bulk modulus of the fluid.

Another purpose is to provide an air-purging means which shall be independent of pump output volume and effective with variable volume pumps.

Another purpose is to provide a hydraulic system having an air-liquid separating structure effective in the high velocity and lower or atmospheric pressure segment of the system.

Another purpose is to provide an air-liquid separating structure capable of creating a liquid velocity in the range of 100 feet per second and above and capable of employing said velocity in a venturi zone effective to evacuate air from the intake side of a pump.

Another purpose is to provide a completely automatic air-liquid separating system operable in response to liquid flow therein and requiring no manual attention or maintenance.

Another purpose is to provide an air-liquid separating structure capable of ready incorporation in existing systems and requiring minimal modification in said systems.

Another purpose is to provide an air-liquid separating structure productive of minimum back pressure and usable

2

with a wide range of liquid viscosities and line flow pressures.

Another purpose is to provide an air-liquid separating structure including an evacuation conduit, a body element having a high velocity venturi section and an outlet baffle and a disperser sleeve and secondary baffle, the elements thereof being independently replaceable with minimum disturbance of the system or elements.

Another purpose is to provide an air-liquid separating structure operable in variable positions and incorporating variable mesh size screens.

Another purpose is to provide a hydraulic system incorporating an air-liquid separating structure having elements immersed in a liquid reservoir.

Another purpose is to provide an air-liquid separating structure of minimum size, weight and cost, having a minimum number of moving parts, of maximum ease of installation and removal and of maximum efficiency and simplicity in operation.

Other purposes may appear from time to time during the course of the specification and claims.

BRIEF DESCRIPTION OF THE DRAWINGS

The invention is illustrated more or less diagrammatically in the accompanying drawings wherein:

FIG. 1 is a schematic view of the system of the invention;

FIG. 2 is an enlarged scale side elevation in partial cross section, illustrating an air-liquid separating structure of the invention;

FIG. 3 is a side view in partial cross section and illustrating a variable form;

FIG. 4 is an illustration, on a reduced scale, of the device of FIG. 2 in one vertical position; and

FIG. 5 is a view similar to that of FIG. 4 and illustrating the device of FIG. 2 in a second vertical position.

Like parts are indicated by like numerals throughout the specification and drawings.

DESCRIPTION OF THE PREFERRED EMBODIMENT

Referring now to the drawings, and particularly to FIG. 1, the numeral 1 generally designates a hydraulic pump. An intake conduit 2 has a filter structure 3 therein. A return or relief valve discharge conduit 4 delivers hydraulic fluid to a lower portion of a hydraulic fluid reservoir 5.

Positioned beneath the minimum working level of hydraulic fluid in reservoir 5, and thus immersed in said fluid, is an air-liquid separating structure indicated generally by the numeral 6. It will be observed that the structure 6 is connected to the delivery end of conduit 4. An outlet for reservoir 5 is indicated at 7. An air evacuation conduit 8 is connected at one of its ends to structure 6 and at its opposite end to an upper portion of filter 3.

It will be realized that various elements may, in accordance with known practice, be incorporated in the hydraulic system of FIG. 1. The machine or element requiring hydraulic fluid, appropriate valves, filters and the like, may, for example, be incorporated at suitable locations in the system. In the interest of clarity and simplicity, and since such elements and their incorporation are well known, they are not shown or further discussed herein. The elements of the system of the invention and their arrangement, substantially as shown in FIG. 1, are thus the hydraulic pump 1, the intake structure for the pump 1, the reservoir 5 and the elements 6 and 8.

Referring now to FIG. 2, in which the structure 6 appears on an enlarged scale, it will be observed that conduit 4 has connected to its outlet end a body 10. Body 10

has an axial, forwardly converging, conical through-bore 11 in which is positioned a forwardly converging, frusto-conical hollow acceleration sleeve 12. The sleeve 12 has a rearward, annular flange portion 13 seated against a correspondingly shaped land 10a of the body 10 and is suitably held thereagainst by the forward edge of conduit 4. It will be observed that the external diameter of the conical portion of sleeve 12 is less than the inner diameter of the bore 11, thus creating a conical, circumferential evacuation chamber 14. A laterally disposed passage 15 is formed in the body 10 and communicates at its inner end with evacuation chamber 14. The outer end of passage 15 is suitably threaded or formed to receive one end of evacuation or air suction conduit 8.

The forward end face of sleeve 12 is outwardly flared or chamfered circumferentially from its inner to its outer edge, as indicated at 17. The outwardly flared surface 17 terminates at the forward mouth of the circumferential evacuation chamber 14 and the surfaces of sleeve 12 presented to liquid flowing therethrough are thus the frusto-conical surface 16 and flared end surface 17.

A bar or strap 20 extends across the forward open end of a ring 21 encompassing the area about the mouths of sleeve 12 and chamber 14 and serving as a baffle against which liquid and air impinges before passing on opposite sides of bar 20. Ring baffle 21 is secured to body 10 by fasteners 21a extending through the wall of ring 20 and securing member 20. A flow disperser, variable orifice-forming member 22 has a conical seat 23 formed and adapted for seating against the surface 17. Spring 24 may engage opposed surfaces of members 20 and 22 to urge the surface 23 toward the surface 17. The member 22 has an axial extension 25 slidably received in a central opening 26 in the member 20.

Removably secured to the body 10 and extending forwardly therefrom is a disperser sleeve 30. The sleeve 30 may be suitably secured to the body 10 as, for example, by a wire coil member 31 having its opposite ends received in suitable pockets 32, 33 formed in the external surface of the body 10.

The sleeve 30 constitutes a circumferential tubular member having a wall 34 formed appropriately of perforated metal and arranged coaxially with sleeve 12 and member 22, the rearward portion of wall 34 encompassing the outlet of sleeve 12 and chamber 14 and extending forwardly therefrom. As illustrated in FIGS. 1 and 2, the disperser sleeve 30 has its lower half covered with a screen formed of fine mesh filtering material, such as a wire screen 35 for example. The forward end of sleeve 30 carries an end cap or baffle 36 having a central aperture 37 normally closed by a relief valve plate 38 held in the position shown by a suitable spring 39 engaging an axial rod 40 secured to the plate 38 and extending through a central aperture in a strap 40a across aperture 37.

Referring now to FIG. 3, a body member 100 is suitably secured to conduit 4. Formed in the body 100 is a forwardly converging conical bore 111 in which an acceleration sleeve 112 is positioned. The outer diameter of sleeve 112 and inner diameter of bore 111 are such as to create the circumferential space or evacuation chamber 114 with which the laterally disposed passage 115, formed in the body 100 communicates. A retainer 113 is suitably supported by fasteners 121 and a spring 124 engages the retainer 113 and a flow disperser member 122.

Member 122 takes the form of a cup-shaped element having its inner base wall 122a presented to the mouth of sleeve 112 and chamber 114. A frusto-conical central portion 122b of base wall 122a rises therefrom to present its domed upper end portion 122c and within the mouth of sleeve 112. It will be observed that sleeve 112 and member 122 are conveniently and economically formed of relatively thin material and that the interpretation thereof provides sufficient seating, as at 112a, 122d, to close the mouth of sleeve 112 when the parts are in the

position shown. The bore 111 in body 100 continues in a reverse-cone counterbore portion 111a paralleling, in spaced relationship, the conical surface of rise 122b. The circumferential wall 122e of member 122 is flared outwardly from base wall 122a and extends rearwardly in the same direction as rise 122b to encompass a forward portion of body 100 within which the mouth of chamber 114 is located. The members 20 and 113 serve as stop means limiting the maximum size of the variable orifice created by members 22, 122 as they move away from their respective seats 17, 112a.

The use and operation of the invention are as follows:

In the system of FIG. 1 the evacuation or air separating conduit or line 8 communicates with the intake side 15 of pump 1, preferably with an upper segment of a filter housing normally present at said intake side. As liquid flows toward reservoir 5 in the system it creates a venturi or subatmospheric pressure zone in member 6 with which line 8 communicates said intake side of pump 1. The 20 pressure differential thus created separates and withdraws air from the liquid just prior to its entry into pump 1 to preclude the compression and consequent heating of the air in the pump and thus to preclude and substantially reduce sludging, corrosion and limitation of efficiency and life of the liquid and pump due to ingress of air thereinto.

The means for creating the pressure differential referred to above operates automatically without human attention or maintenance and in response to the flow of 30 liquid or hydraulic fluid in line 4 to member 6. Said flow accelerates in sleeve 12 or 112. With a normal flow in conduit 4 of the order of 15 ft./sec., for example, the flow will accelerate to a speed of the order of 60 ft./sec. in sleeve 12, 112. In response to said flow, valve or disperser member 22, 122 will open, the springs 24, 124 being of predetermined, normally relatively light forces. In an upwardly directed vertical position the spring may be discarded and gravity may be relied upon to close member 22, for example. In any case the forces affecting 40 the operation of member 22, 122 are known and preset to provide for operation of the device at desired, normally relatively low, flow line forces. In the example cited, the liquid accelerates from an order of 60 ft./sec. in sleeve 12, 112 to a speed in the order of 100 ft./sec. 45 or more as it flows through the variable orifice created by opposed seating faces 17, 23 of members 12, 22 or as at 112a, 122d of members 112, 122, to produce a venturi or subatmospheric pressure zone at the mouth of and within chamber 14, 114, as well as within conduit 8. Thus air is drawn through conduit 8 from the intake 50 of pump 1 to the area outwardly of and beyond the mouth of chamber 14, 114.

The liquid flows past the mouth of chamber 14, 114 at a velocity of 100 ft. per second to overcome air-liquid 55 cohesive forces and is dispersed by members 22, 122 into disperser sleeve 30. Air drawn from chamber 14, 114 and in the liquid flowing at high velocity thereacross, due to their differing densities, will be propelled at different 60 velocities and will tend to separate as the liquid flows in an outwardly expanding pattern member 22 or along and from the rearwardly disposed edge of wall 122e of member 122. Thereafter, the disperser sleeve 30 provides a dispersal and separation of said air, the hydraulic fluid or liquid flowing primarily through screen 35 and air through the relatively large perforations in sleeve 30. 65 Facilitating separation of air and liquid by means of velocities and through sleeve 30 and screen 35 serves to increase the density and bulk modulus of the fluid. While the structure of the invention is operative at velocities lower than those listed herein, its effectiveness is increased 70 at the velocities specified and higher.

When sleeve 30 is positioned horizontally, as in FIGS. 1 and 2, the bottom portion of its circumference is conveniently covered with a partial screen 35. When the structure is positioned vertically, a circumferential screen

35 is arranged about the lower portion of sleeve 30 to provide for ready rise of air into the upper area of reservoir 5 devoid of liquid for appropriate discharge to atmosphere. Suitable connections (not shown) may be provided for alternate or sliding relationship of sleeve 30 and screen 35 to permit utilizing of the same structure in either of the positions of FIGS. 4 and 5. The member 6, comprising elements 10-40, or with the elements of FIG. 3 substituted for corresponding elements of FIG. 2, is positioned beneath the surface or working level of fluid in reservoir 5, thus precluding malfunction in the event of conduit leakage or slightly loose connections.

Should system contaminants seriously clog the openings in disperser sleeve 30 and screen 35, the relatively low pressure relief valve structure 36-40a will open to preclude excessive system back pressure and consequent malfunction of valves (not shown) in the system.

Sleeve 30 and screen 35, with secondary baffle and relief valve structure 36-40a, constitute a barrier member which is easily removed from and installed on a body such as body 10 without disturbance to the body, to conduit 8 or to sleeve 12 or member 22 and associated elements. Similarly, conduit 8 can be installed and removed from body 10, 100 without disturbance of such a sleeve or any of the other elements of FIG. 2. Member 6 can be varied in position with a mere change in location of mesh screen 35 which may be accomplished with ease and without disturbing any other elements.

While the system and structure is disclosed herein in relation to hydraulic fluid and finds a major application thereto, it will be realized that the same may be applicable to the separation of air or gases from other liquids without departing from the nature and scope of the invention.

The embodiments of the invention in which an exclusive property or privilege is claimed are defined as follows:

1. For use in a hydraulic fluid pressure system having a pump, an intake element for said pump, a hydraulic fluid reservoir and a conduit delivering hydraulic fluid to said reservoir, means for separating air from said fluid at said intake element, including a fluid flow-accelerating device in said reservoir and connected to said delivering conduit for reception of fluid therefrom, an evacuation conduit communicating said intake element with said accelerating device, a disperser device secured to said accelerating device and positioned to receive fluid therefrom, said disperser device including a barrier having openings of varying dimensions at upper and lower positions thereof for passage of air through some of said openings and of fluid through others of said openings.

2. The structure of claim 1 characterized by and including an imperforate baffle at the downstream end of said barrier and a relief valve carried by said baffle and formed and adapted to open a passage through said baffle in response to fluid pressure at said barrier beyond a predetermined level.

3. A liquid-flow-accelerating, subatmospheric pressure zone producing device responsive to the flow of liquid therethrough, said device comprising a body, a frusto-conical, inwardly converging bore in said body, a frusto-conical, inwardly converging sleeve in said bore and having a portion spaced from said bore to define an evacuation chamber about the smaller end of said sleeve, a frusto-conical, orifice-creating, liquid dispersing member having its smaller end portion urged into a position closing said smaller sleeve end and movable therefrom in response to the flow of liquid through said sleeve to define an outwardly diverging conical orifice in communication with said chamber and effective to accelerate the flow of fluid across an end portion of said chamber.

4. The structure of claim 3 wherein said sleeve has an

inwardly converging end face at its smaller end and said orifice-creating, liquid dispersing member has a conical end face formed and adapted to seat on said sleeve end face.

5. The structure of claim 3 wherein said sleeve and orifice-creating, liquid dispersing member are formed of relatively thin material and said body includes a reverse cone counterbore flaring outwardly from said throat and defining with the opposed, substantially parallel surface of said last-named member a conical orifice in communication with said chamber.

6. The structure of claim 3 characterized by and including a passage formed in said body and communicating said chamber with the area outside said body.

7. The structure of claim 3 wherein said chamber is of relatively thin frusto-conical configuration extending substantially the length of said sleeve and bore and characterized by and including a passage formed in said body and communicating a portion of said chamber adjacent the larger end of said sleeve with the area outside said body.

8. The structure of claim 8 characterized by and including means limiting the movement of said orifice-creating, liquid dispersing member away from said smaller sleeve end.

25 9. The structure of claim 3 characterized by and including an air-fluid dispersing and separating element, said element comprising a barrier member removably secured to said body and encompassing the liquid outlet thereof to receive all of said liquid as it flows from the 30 orifice created by said orifice-creating, liquid-dispersing member, said barrier member having an upper and lower portion, said upper portion having relatively large openings therein for the passage of air therethrough, said lower portion having relatively smaller openings for the 35 passage of liquid and resistance to the passage of air therethrough.

10. The structure of claim 10 characterized by and including an outwardly conical circumferential wall on said last-named member positioned to receive fluid from said defined orifice and to reverse the direction of said flow.

11. In a hydraulic system, a pump having an intake side, a hydraulic fluid reservoir, a conduit delivering fluid to said reservoir, a fluid-flow accelerating, subatmospheric pressure zone creating device connected to the delivery end of said delivering conduit and positioned to discharge air and fluid into said reservoir, said device being operative in response to flow of fluid therethrough, a conduit communicating said pump intake side with the subatmospheric zone of said device, a barrier member between the outlet of said device and the area within said reservoir, said barrier having openings in its upper portion of a size facilitating the passage of air therethrough and openings in its lower portion of a size to permit the 55 passage of fluid and resist the passage of air therethrough.
